LASTING MACHINE

John T. Lancaster, Newton, Mass., assignor to
 United Shoe Machinery Corporation, Flemington, N. J., a corporation of New Jersey

Application September 30, 1948, Serial No. 51,981

22 Claims. (Cl. 12—12.4)

1

This invention relates to lasting machines, and more particularly to machines for lasting end portions of shoes. The invention is herein shown as embodied in means for lasting the toe ends of shoes, for which use such means is especially well adapted, but in some aspects the invention is also applicable to heel-end lasting.

In lasting the toe ends of shoes it is the common practice to use a pair of wipers which are shaped to conform to the contour of the edge of a last bottom pattern corresponding to a shoe of a given style and size. Although this has been regarded as the most satisfactory manner of shaping such wipers, it will be evident that in operating on a shoe of that style and size the wipers, because of the added thickness of the upper materials, will not conform exactly to the contour of the upper opposite the edge face of the insole and in the case of a Goodyear welt shoe will not conform exactly to the contour of the upstanding margin of the upper pressed inwardly against the usual lip or shoulder on the insole at some distance from its edge. In the wiping of the upper heightwise of the last, moreover, commonly known as the upwiping operation, the approach to conformity of the wipers to the contour of the upper around the toe end of the last will vary at different distances from the edge of the insole. Since, also, it is the common practice, for the sake of economy, to use the same wipers in lasting shoes of several different sizes, it will be evident that they will not fit some of the shoes so well as others. In fact, moreover, that for shoes which differ substantially in style or size differently formed wipers are commonly required adds substantially to the cost of machine equipment.

It is an object of the present invention to provide wiping means which will conform itself to the different contours of different portions of a shoe and to the contours of shoes of different styles and sizes, thus improving the results obtained in the lasting operation, saving the time required for changing wipers and reducing the expense of the equipment. To this end, the construction herein shown comprises a novel wiper formed of resiliently flexible material and arranged to extend continuously around the end of the shoe. To permit such a flexible wiper to be properly controlled in the upwiping operation and in thereafter pressing the upper heightwise of the last on the margin of the insole, it is so formed that it extends a substantial distance outwardly from the shoe, its outer portion being engaged by and confined between portions of a

2

wiper support which face each other heightwise of the shoe and relatively to which the wiper is slidably movable lengthwise and widthwise of the shoe in the lasting operation. As further herein illustrated, the outer portion of the wiper thus confined is rectangular in planes intersecting it transversely of the edge of the shoe bottom, while its inner portion forms an acute angle in such planes to provide a wiping edge for engagement with the upper. Each of two alternative forms of wiper so shaped and herein shown is of hollow construction to provide a recess extending through it lengthwise of the edge of the shoe bottom, one such form comprising a coil spring made of a rectangular strip of material formed to produce the angular shape above described and the other form comprising an elongated hollow member having a series of slits extending part way through it in directions transverse to the edge of the shoe bottom to increase its flexibility. This form of wiper is operated by means directly connected to its opposite ends for moving it bodily lengthwise of the shoe and for flexing it widthwise of the shoe, while the first-mentioned form of wiper is operated and controlled by means including a flexible cable extending through the recess therein.

The invention further provides novel mechanism for operating either form of flexible wiper above described. The mechanism herein shown for this purpose comprises a pair of arms which are mounted for bodily movements lengthwise of the shoe to move the wiper as a whole in that direction and for swinging movements each about an axis extending heightwise of the shoe to flex the wiper widthwise of the shoe, together with spring means controlling the arms and yieldable in response to resistance of the shoe to the bodily movement or the swinging movement of either arm independently of the other. More particularly, as herein illustrated, the arms are thus mounted on other arms which extend widthwise of the shoe and are carried bodily lengthwise of the shoe by an operating member, these other arms being pivotally mounted on the operating member to permit them to swing lengthwise of the shoe but being normally held, each independently of the other, against such swinging movement by spring means which is yieldable in response to resistance of the shoe to bodily movement of the first-mentioned arms. The swinging movements of the first-mentioned arms to flex the wiper are effected by cam means acting on the arms in response to their bodily movements lengthwise of the shoe through springs which are

independently yieldable in response to resistance of the shoe to the swinging of the arms.

The above and other features of the invention, including various novel details of construction and combinations of parts, will now be more particularly described with reference to the accompanying drawings and thereafter pointed out in the claims.

In the drawings,

Fig. 1 is mainly a plan view, with parts broken away, showing toe-lasting means in which novel features of the invention are embodied;

Fig. 2 is a section on the line II—II of Fig. 1, showing the relation of the wiper to a shoe of the Goodyear welt type substantially at the beginning of the upwiping operation;

Figs. 3 and 4 are views similar to Fig. 2 showing the relation of the wiper to the shoe at the end of the upwiping operation and at the end of the operation of wiping the marginal portion of the upper inwardly over the insole respectively;

Fig. 5 is a view similar to a portion of Fig. 1, but showing an alternative form of wiper;

Fig. 6 is a section similar to Fig. 2 on the line VI—VI of Fig. 5;

Fig. 7 is a view corresponding to Fig. 4 but showing the alternative wiper; and

Fig. 8 shows a portion of the alternative wiper in plan as it appears at a certain stage in its manufacture.

The invention is herein shown, for purposes of illustration, as embodied in means adapted for use in a modification of a bed-lasting machine of the type disclosed in United States Letters Patent No. 1,018,477, granted on February 27, 1912, on an application of Matthias Brock's. A machine of that type includes a toe wiper support which may be adjusted in various ways relatively to a shoe positioned bottom upward in the machine and which carries a pair of toe-embracing wipers, the support being moved upwardly by a treadle to cause the wipers, which are held against the upper by a hand lever, to wipe the upper heightwise of the last, i. e., to perform the upwiping operation. By the same treadle, after the wipers have been operated by the hand lever to wipe the marginal portion of the upper inwardly over the insole, they are forced downwardly to increase their pressure on the upper over the insole.

The present invention provides, in place of such a pair of toe-embracing wipers, a flexible wiper constructed and arranged to extend continuously around the toe end of the shoe and to conform itself to the contour of the shoe throughout the toe-lasting operation. This wiper and the means for operating it to press the upper around the toe against the last and to wipe its marginal portion inwardly over the insole are supported as hereinafter described by a plate 2 which, it will be understood, may be secured in any suitable manner to the toe wiper support of a machine of the above-mentioned type. The form of wiper shown at 4 in Figs. 1 to 4 inclusive comprises a coil spring made of a strip of resiliently flexible material, preferably metal, which is rectangular in cross section. In order that such a flexible wiper may be so controlled as to render it properly effective in the upwiping operation and in pressing the upper downwardly on the insole, it is so formed as to extend a substantial distance outwardly from the shoe and its outer portion is engaged by and confined between upper and lower portions 6 and 8 of a wiper-supporting member 10 which is formed to extend around the toe and is secured

on the upper ends of a pair of vertical studs 12 fast on the plate 2. The strip of material of which the wiper 4 is made is so formed that the outer portion of the wiper confined as above described is rectangular in planes intersecting it transversely of the edge of the shoe bottom and has flat upper and lower faces engaged by the portions 6 and 8 of the support, as shown in Figs. 2, 3 and 4, while its inner portion next to the shoe forms an acute angle in such planes to provide a wiping edge 14 for engagement with the upper. With the wiper curved to embrace the toe as shown in Fig. 1, its wiping edge is practically continuous all around the toe.

To apply the wiper 4 to the upper preparatory to the upwiping operation and to operate it for wiping the marginal portion of the upper inwardly over the insole it is moved bodily lengthwise of the shoe in sliding engagement with its support 10 and is also flexed widthwise of the shoe. For this purpose there is provided a flexible metal cable 16 extending through the wiper around the toe end of the shoe and secured at its opposite ends to blocks 18 which are pivotally mounted on studs 20 carried by arms 22 extending generally lengthwise of the shoe. These arms are pivotally mounted on studs 24 for swinging movements widthwise of the shoe, the studs being mounted on the outer ends of other arms 26 which extend widthwise of the shoe and are both pivotally mounted at their inner ends on a vertical stud 28 carried by an operating bar 30 which is slidably movable lengthwise of the shoe along guideways 32 on upwardly extending portions of the plate 2, the bar extending through an opening in the wiper support 10. Secured to a lug 34 on the bar 30 is a leaf spring 36 the opposite end portions of which bear against the arms 26 to control them with respect to swinging movements about the stud 28, the spring holding the arms normally in positions determined by the engagement of pins 38 on the arms with a crossbar 40 mounted in the stud 28. For moving the bar 30 lengthwise of the shoe there is provided a hand lever 42 pivotally mounted on a stud 44 on the plate 2 and having therein a slot 46 in which is slidably mounted a block 48, the block being provided with a stud 50 mounted to turn in the bar 30. It will thus be evident that as the bar 30 is moved toward the shoe it carries the arms 26 and 22 bodily with it and thus moves the wiper 4 as a whole in the same direction to apply it to the shoe prior to the upwiping operation and later to wipe the marginal portion of the upper inwardly over the insole. When the resistance of the shoe to the bodily movement of either of the arms 22 and of the corresponding arm 26 becomes great enough the portion of the spring 36 which controls those arms will yield independently of the portion thereof which controls the other arms 22 and 26 in response to continued movement of the bar 30. Provision is thus afforded, regardless of the shape of the shoe, for applying to both ends of the cable 16 the force required for the best results in the toe-lasting operation.

The swinging movements of the arms 22 about the studs 24 to flex the wiper as required widthwise of the shoe are effected in response to their bodily movements lengthwise of the shoe. For this purpose there is associated with each of the arms 22 an arm 52 mounted to swing about the same stud 24 and having thereon a roll 54 engaged by a cam 56 fast on the plate 2. A spring 58 connected to the two arms 52 holds the rolls 54 at all times against the cams. Between each arm

22 and the arm 52 associated therewith is a compression spring 60 through which the arm 22 is swung by the arm 52 as the latter is swung by the corresponding cam 56. It will be evident that either spring 60 is yieldable independently of the other in response to resistance of the shoe to the swinging movement of the corresponding arm 22.

When the hand lever 42 is retracted the arms 52 are swung toward each other by the spring 58 as permitted by the cams 56, and shoulders 62 on these arms engage shoulders 64 on the arms 22 to swing the latter away from the shoe and thus to permit the portions of the resilient wiper at the sides of the toe to spring outwardly. At the same time the arms 22 are retracted bodily lengthwise of the shoe by the bar 30. To assist in retracting the wiper bodily in the same direction the bar 30 is provided at its inner end with projections 66 which extend inwardly between convolutions of the wiper and engage the inner surfaces of two of these convolutions.

From the foregoing description it will be understood that in the toe-lasting operation the lasting mechanism shown in Fig. 1 is moved upwardly to cause the wiper 4 to perform the upwiping operation by use of the treadle provided for this purpose in a machine of the type to which the invention is shown as applied. The wiper 4 is thus moved from the position illustrated in Fig. 2 to that illustrated in Fig. 3. During this operation the operator, through the hand lever 42, holds the wiper pressed inwardly against the upper, the wiper conforming itself at all times to the contour of the shoe however the contour may vary at different distances from the edge of the shoe bottom. The operator may, as customary, repeat the upwiping operation one or more times while using hand pincers to adjust and control the margin of the upper. Thereafter he further operates the wiper by the hand lever to wipe the marginal portion of the upper inwardly over the insole and, if the shoe is one of the Goodyear welt type as shown, to press a portion of the margin of the upper in upstanding position against a lip *a* on the insole as illustrated in Fig. 4, the wiper further conforming itself to the contour of the portion of the upper thus pressed against the lip. By use of the treadle the wiper is then forced downwardly to increase its pressure on the portion of the upper between it and the feather of the insole. It will be evident that, despite its flexibility, the wiper is held sufficiently rigid heightwise of the shoe by the portions 6 and 8 of its support 10 both in the upwiping operation and in the pressing of the upper down on the insole.

In Figs. 5, 6 and 7 is shown an alternative form of wiper 68 which may be used instead of the wiper 4 shown in Fig. 1. The wiper 68 is made of an elongated hollow member 70 (Fig. 8) of resiliently flexible material, this member being angular in cross section and being provided with a series of slits 72 extending part way through it crosswise thereof to increase its flexibility. The outer portion of the wiper 68, confined between the portions 6 and 8 of the support 10 similarly to the corresponding portion of the wiper 4 of Fig. 1, thus comprises a series of segments 74 spaced from one another and rectangular in planes transverse to the edge of the shoe bottom. The inner portion of the wiper comprises an inclined strip 76 which is continuous all around the toe and forms an acute angle with the lower portion of each segment 74 to provide a wiping edge 78 for engagement with the upper. The opposite ends of the wiper 68 are connected to the

arms 22 by studs 80. Accordingly these arms are directly effective to flex the wiper inwardly and to retract it widthwise of the shoe and they also serve in combination with the projections 66 on the bar 30, which engage two of the segments 74, to retract it lengthwise of the shoe. In other respects the manner of operation of the wiper 68 is the same as that of the wiper 4 shown in Fig. 1.

Having described the invention, what I claim is new and desire to secure by Letters Patent of the United States is:

1. In a lasting machine, a one-piece wiper of flexible resilient material arranged to extend continuously around the toe end of the upper of a shoe on a last and conformable lengthwise and widthwise of the shoe to the contour thereof in response to pressure of the shoe against it, said wiper being angular in cross-section to provide a wiping edge for engagement with the upper, a support for the wiper also arranged to extend around the toe end of the shoe and having portions facing each other heightwise of the shoe for engaging and confining the wiper between them and for thereby rendering it effective to wipe the upper in a direction heightwise of the last and thereafter to press a portion of the upper in the opposite direction upon an insole on the last in response to relative movements of said support and the last, and means for moving the wiper lengthwise of the shoe relatively to the portions of the support thus engaging it and for also flexing it widthwise of the shoe to apply it in conformity to the contour of the shoe and to wipe the marginal portion of the upper inwardly over the insole.

2. In a lasting machine, a one-piece wiper of flexible resilient material arranged to extend continuously around the toe end of the upper of a shoe on a last and conformable lengthwise and widthwise of the shoe to the contour thereof in response to pressure of the shoe against it, said wiper forming an acute angle in cross-section to provide a wiping edge for engagement with the upper, a support for the wiper also arranged to extend around the toe end of the shoe and having portions facing each other heightwise of the shoe for engaging and confining the wiper between them and for thereby rendering it effective to wipe the upper in a direction heightwise of the last and thereafter to press a portion of the upper in the opposite direction upon an insole on the last in response to relative movements of said support and the last, the wiper having flat faces engaged by said portions of the support, and means for moving the wiper lengthwise of the shoe relatively to the portions of the support thus engaging it and for also flexing it widthwise of the shoe to apply it in conformity to the contour of the shoe and to wipe the marginal portion of the upper inwardly over the insole.

3. In a lasting machine, a one-piece wiper of flexible resilient material arranged to extend continuously around the toe end of the upper of a shoe on a last and conformable lengthwise and widthwise of the shoe to the contour thereof in response to pressure of the shoe against it, said wiper being hollow to provide a recess therein extending around the toe end of the shoe but closed on the side toward the shoe and forming an acute angle in cross-section to provide a wiping edge for engagement with the upper, a support for the wiper also arranged to extend around the toe end of the shoe and having portions facing each other heightwise of the shoe

for engaging and confining the wiper between them and for thereby rendering it effective to wipe the upper in a direction heightwise of the last and thereafter to press a portion of the upper in the opposite direction upon an insole on the last in response to relative movements of said support and the last, and means for moving the wiper lengthwise of the shoe relatively to the portions of the support thus engaging it and for also flexing it widthwise of the shoe to apply it in conformity to the contour of the shoe and to wipe the marginal portion of the upper inwardly over the insole.

4. In a lasting machine, a wiper comprising a coil spring arranged to extend around the toe end of the upper of a shoe on a last and conformable to the contour of the shoe in response to pressure of the shoe against it, said spring being formed in angular shape to provide a wiping edge for engagement with the upper, a support for said wiper also arranged to extend around the toe end of the shoe and having portions facing each other heightwise of the shoe for engaging and confining the wiper between them and for thereby rendering it effective to wipe the upper in a direction heightwise of the last and thereafter to press a portion of the upper in the opposite direction upon an insole on the last in response to relative movements of said support and the last, the wiper having flat faces slidingly engaging said portions of the support, and means for moving the wiper lengthwise of the shoe relatively to said support and for also flexing it widthwise of the shoe to apply it in conformity to the contour of the shoe and to wipe the marginal portion of the upper inwardly over the insole.

5. In a lasting machine, a wiper comprising a coil spring arranged to extend around the toe end of the upper of a shoe on a last and conformable to the contour of the shoe in response to pressure of the shoe against it, said spring being formed in angular shape to provide a wiping edge for engagement with the upper, a support for said wiper also arranged to extend around the toe end of the shoe and having portions facing each other heightwise of the shoe for engaging and confining the wiper between them and for thereby rendering it effective to wipe the upper in a direction heightwise of the last and thereafter to press a portion of the upper in the opposite direction upon an insole on the last in response to relative movements of said support and the last, a flexible cable extending through the wiper around the end of the shoe, and means connected to the ends of said cable for moving the wiper bodily lengthwise of the shoe and for flexing it widthwise of the shoe to apply it in conformity to the contour of the shoe and to wipe the marginal portion of the upper inwardly over the insole.

6. In a lasting machine, a wiper of resiliently flexible material arranged to extend continuously around the toe end of the upper of a shoe on a last and conformable lengthwise and widthwise of the shoe to the contour thereof in response to pressure of the shoe against it, said wiper comprising a hollow member having a series of slits extending part way through it in directions transverse to the edge of the shoe bottom to increase its flexibility, a support for the wiper also arranged to extend around the toe end of the shoe and having portions facing each other heightwise of the shoe for engaging and confining the wiper between them and for there-

by rendering it effective to wipe the upper in a direction heightwise of the last and thereafter to press a portion of the upper in the opposite direction upon an insole on the last in response to relative movements of said support and the last, and means connected to the ends of said wiper for moving it bodily lengthwise of the shoe relatively to said support and for also flexing it widthwise of the shoe to apply it in conformity to the contour of the shoe and to wipe the marginal portion of the upper inwardly over the insole.

7. In a lasting machine, a one-piece wiper of flexible resilient material arranged to extend continuously around the toe end of the upper of a shoe on a last and conformable lengthwise and widthwise of the shoe to the contour thereof in response to pressure of the shoe against it, said wiper being angular in cross-section to provide a wiping edge for engagement with the upper, a support for the wiper also arranged to extend around the toe end of the shoe and having portions facing each other heightwise of the shoe for engaging and confining the wiper between them and for thereby rendering it effective to wipe the upper in a direction heightwise of the last and thereafter to press a portion of the upper in the opposite direction upon an insole on the last in response to relative movements of said support and the last, a pair of arms mounted for bodily movements lengthwise of the shoe and also for swinging movements each about an axis extending heightwise of the shoe, and means for moving the wiper as a whole lengthwise of the shoe relatively to the portions of the support thus engaging it by the bodily movements of said arms and for also flexing it by the swinging movements of the arms to apply it in conformity to the contour of the shoe and to wipe the marginal portion of the upper inwardly over the insole.

8. In a lasting machine, a wiper of flexible material for wiping the toe end of the upper of a shoe on a last heightwise of the last and for wiping the marginal portion of the upper inwardly over an insole on the last, said wiper being arranged to extend continuously around the toe end of the shoe and being conformable lengthwise and widthwise of the shoe to the contour thereof in response to pressure of the shoe against it, a pair of arms mounted for bodily movements lengthwise of the shoe to move the wiper as a whole in that direction and for swinging movements each about an axis extending heightwise of the shoe to flex the wiper widthwise of the shoe, and operating means for thus moving said arms to apply the wiper in conformity to the contour of the shoe and to wipe the marginal portion of the upper inwardly over the insole, said operating means including portions associated respectively with the different arms and each yieldable independently in response to resistance of the shoe to the bodily movement of the arm associated therewith.

9. In a lasting machine, a wiper of flexible material for wiping the toe end of the upper of a shoe on a last heightwise of the last and for wiping the marginal portion of the upper inwardly over an insole on the last, said wiper being arranged to extend continuously around the toe end of the shoe and being conformable lengthwise and widthwise of the shoe to the contour thereof in response to pressure of the shoe against it, a pair of arms mounted for bodily movements lengthwise of the shoe to move the wiper as a

whole in that direction and for swinging movements each about an axis extending heightwise of the shoe in a location farther from the shoe than the wiper to flex the wiper widthwise of the shoe, and operating means for thus moving said arms to apply the wiper in conformity to the contour of the shoe and to wipe the marginal portion of the upper inwardly over the insole, said operating means including portions associated respectively with the different arms and each yieldable independently in response to resistance of the shoe to the swinging movement of the arm associated therewith.

10. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of members mounted for bodily movements lengthwise of the shoe to move the wiper as a whole in that direction and for swinging movements each about an axis extending heightwise of the shoe to flex the wiper widthwise of the shoe, and mechanism for thus moving said members to operate the wiper, said mechanism including spring means yieldable in response to resistance of the shoe to the bodily movement or the swinging movement of either of said members independently of the other.

11. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of arms mounted for bodily movements lengthwise of the shoe to move the wiper as a whole in that direction and for swinging movements each about an axis extending heightwise of the shoe in a location farther from the shoe than the wiper to flex the wiper widthwise of the shoe, and operating means for thus moving said arms to operate the wiper, said operating means including an operating member movable lengthwise of the shoe and spring means controlled by said member for imparting the bodily movements to the arms, said spring means being yieldable in response to resistance of the shoe to the bodily movements of the arms.

12. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of arms mounted for bodily movements lengthwise of the shoe to move the wiper as a whole in that direction and for swinging movements each about an axis extending heightwise of the shoe to flex the wiper widthwise of the shoe, and operating means for thus moving said arms to operate the wiper, said operating means including an operating member movable lengthwise of the shoe and spring means controlled by said member for imparting the bodily movements to the arms, said spring means being yieldable in response to resistance of the shoe to the bodily movement of either arm independently of the other.

13. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of

arms mounted for bodily movements lengthwise of the shoe to move the wiper as a whole in that direction and for swinging movements each about an axis extending heightwise of the shoe to flex the wiper widthwise of the shoe, and operating means for thus moving said arms to operate the wiper, said operating means including an operating member movable lengthwise of the shoe and carrying the arms and spring means also carried by said member and controlling the arms, said spring means being yieldable in response to resistance of the shoe to the bodily movement of either arm independently of the other.

14. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of arms arranged to extend lengthwise of the shoe for operating the wiper, another pair of arms arranged to extend widthwise of the shoe and on which said first-named arms are pivotally mounted for swinging movements widthwise of the shoe to flex the wiper, and means for moving said other arms bodily lengthwise of the shoe to cause the first-named arms to move the wiper as a whole in that direction, said other arms being mounted to swing yieldingly each about an axis extending heightwise of the shoe in response to resistance of the shoe to such movement of the wiper.

15. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of arms arranged to extend lengthwise of the shoe for operating the wiper, another pair of arms arranged to extend widthwise of the shoe and on which said first-named arms are pivotally mounted for swinging movements widthwise of the shoe to flex the wiper, an operating member movable to carry said other arms bodily lengthwise of the shoe to cause the first-named arms to move the wiper as a whole in that direction, the other arms being pivotally mounted on said operating member to swing lengthwise of the shoe, and spring means arranged to permit such swinging of the other arms in the lasting operation only in response to resistance of the shoe to the movement of the wiper.

16. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of arms mounted for bodily movements lengthwise of the shoe to move the wiper as a whole in that direction and for swinging movements each about an axis extending heightwise of the shoe to flex the wiper widthwise of the shoe, means for imparting the bodily movements to the arms, and additional means for swinging the arms in response to their bodily movements, said additional means including portions yieldable in response to resistance of the shoe to the swinging of the arms.

17. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of arms

mounted for bodily movements lengthwise of the shoe to move the wiper as a whole in that direction and for swinging movements each about an axis extending heightwise of the shoe to flex the wiper widthwise of the shoe, means for imparting the bodily movements to the arms, cam means relatively to which the arms are thus bodily movable for swinging them in response to their bodily movements, and springs through which the arms are swung by said cam means, said springs being yieldable in response to resistance of the shoe to the swinging of the arms.

18. In a lasting machine, a wiper of flexible material arranged to extend continuously around an end of the upper of a shoe on a last for wiping the upper into lasted position, said wiper being flexible lengthwise and widthwise of the shoe to conform to the contour thereof, a pair of arms mounted for bodily movements lengthwise of the shoe to move the wiper as a whole in that direction and for swinging movements each about an axis extending heightwise of the shoe to flex the wiper widthwise of the shoe, means for imparting the bodily movements to the arms, cam means relatively to which the arms are thus bodily movable for swinging them in response to their bodily movements, members arranged to be operated by said cam means thus to swing the arms, and springs for transmitting movement from said members to the arms.

19. In a lasting machine, a wiper comprising a hollow member of resiliently flexible material arranged to extend continuously around an end of the upper of a shoe on a last for wiping the upper into lasted position, said member being of angular contour in planes extending transversely of the edge of the shoe bottom to provide a wiping edge for engagement with the upper and having in locations farther outward than its wiping edge a series of spaced-apart portions angular in cross section lengthwise of the edge of the shoe bottom and relatively movable lengthwise of the edge of the shoe bottom in response to flexure of the member in the wiping operation.

20. In a lasting machine, a wiper of resiliently flexible material arranged to extend continuously around an end of the upper of a shoe on a last

for wiping the upper into lasted position, said wiper comprising a coil spring made of a strip of material angular in cross-section and formed in angular shape to provide a wiping edge for engagement with the upper.

5 21. In a lasting machine, a wiper of resiliently flexible material for wiping an end portion of an upper into lasted position, said wiper comprising a one-piece hollow member thus resiliently flexible lengthwise and widthwise of the shoe and formed to extend continuously around the end of the shoe, said member having a series of slits extending only part way through it in directions transverse to the edge of the shoe bottom to increase its flexibility.

10 22. In a lasting machine, a wiper of resiliently flexible material arranged to extend continuously around an end of the upper of a shoe on a last for wiping the upper into lasted position, said wiper comprising a hollow member thus resiliently flexible lengthwise and widthwise of the shoe and having a series of slits extending part way through it in directions transverse to the edge of the shoe bottom to increase its flexibility, 20 and means connected to the opposite ends of said member for moving it bodily lengthwise of the shoe and for flexing it widthwise of the shoe.

JOHN T. LANCASTER.
